UNITED STATES PATENT OFFICE.

STEPHEN F. LUCAS, OF VALLEY PARK, MISSOURI.

HEADLIGHT.

Application filed September 9, 1925. Serial No. 55,363.

Figure 1 is a central vertical section of the invention.

Figure 2 is a front view of the same.

The invention has relation to head-lights for automobiles and other vehicles, having for an object to provide an improved head-light designed to reduce the glare to a minimum without sacrifice to sufficient illumination.

10 The invention consists in the novel construction and combinations of parts as set forth in the appended claim.

In the accompanying drawings illustrating an embodiment of the invention, the 15 numeral 1 designates the reflector of the form of a segment of a hollow sphere, and 2, 2' electric light bulbs fixed adjacent the reflector and including a central bulb 2' and an annular series of bulbs 2, located adjacent 20 the outer margin of the reflector and spaced apart by approximately equal distances from each other and from said central bulb in front view.

These light bulbs are of low candle power, 25 each usually eight candle power or under, although four candle power bulbs give excellent results in practice, and the annular series of bulbs may be arranged each radially of the reflector or may project straight out- 30 wardly therefrom as does the central bulb 2'.

The ordinary power of a focal light in a headlight reflector is from twenty one to thirty two candle power, and therefore the combined candle power of the seven light 35 bulbs of four candle power each would be approximately the same.

The mirror surface of the reflector being spherical will distribute the light rays from

said bulbs fan fashion, and it is found in practice that with the seven light bulbs of 40 four candle power each arranged as stated, the roadway will be illuminated sufficiently to make driving safe, objects being distinguishable at a distance of 150 feet, and the sides of the road will be illuminated also 45 to cause side roads to be visible at a distance of from 50 to 75 feet and road signs readable at either side of the road with ease.

In view of the fact that sufficient illumination is given both in front and at the sides 50 of the road, spot lights are rendered unnecessary.

By arranging the light bulbs as stated it is designed to produce an illumination in a fan shaped field of more equal and softer 55 character with a given expenditure of candle power in the light bulbs, the segmental spherical surface reflector giving the best results.

I claim:—

60 In a non-glare vehicle headlight, a segmental spherical surface reflector, a cover glass contacting with the margin of said reflector, a central light socket, an annular series of light sockets intersecting said reflector near the marginal portion thereof and spaced apart from each other and from 65 said central light socket by substantially equal distances, and a light bulb of low candle power in each socket, the combined 70 candle power of said light bulbs being approximately equal to the candle power of the focal light bulb usually employed.

In testimony whereof I affix my signature.

STEPHEN F. LUCAS.
